UNITED STATES PATENT OFFICE.

JACOB T. LUTZ, OF RANDOLPH, SOUTH DAKOTA.

TRACE-CARRIER.

1,003,929.

Specification of Letters Patent. Patented Sept. 19, 1911.

Application filed April 4, 1911. Serial No. 618,917.

To all whom it may concern:

Be it known that I, JACOB T. LUTZ, a citizen of the United States, residing at Randolph, in the county of Brown and State of South Dakota, have invented new and useful 5 Improvements in Trace-Carriers, of which the following is a specification.

This invention relates to trace carriers, and the object thereof is to provide such a 10 device with means whereby the free ends of the trace may be held up when not in use, and prevented from coming down and catching in the objects on the ground or interfering with the free movement of the animal.

15 To this end, the invention resides in the novel construction and arrangement of parts hereinafter fully described and claimed.

In the drawings—Figure 1 is a perspective view of the trace carrier. Fig. 2 is a 20 sectional view upon the line 2—2 of Fig. 1. Fig. 3 is a longitudinal sectional view taken at right angles to Fig. 2.

Like numerals of reference designate corresponding parts throughout the several 25 views.

Referring to the drawings, the carrier is of a skeleton form, having its longitudinal ends provided with openings 1 which are adapted to receive the back and crupper 30 straps of the harness. The longitudinal edges of the frame are also provided with openings 2, the same being adapted to receive the breeching straps of the harness. The skeleton frame is provided with a pair 35 of upwardly curved guard members 3, the same being arranged adjacent the openings 1, and the said guards having their inner faces curved or of an arcuate formation as clearly illustrated in Fig. 1 of the drawings.

40 The transverse edges of the central or hollow portion of the frame is provided with a pair of arched fingers 4 and 5. The finger

4 has its upper portion provided with a depression 6 and its lower edge formed with a depending lip 7. The finger 5 has its upper face provided with a recessed pocket 8, the latter adapted to receive the flattened 45 spring member 9. This spring is secured within the pocket in any desired or preferred manner, and the said spring has its free end upturned as at 10 and is adapted to be received within the recess 6 of the finger 4.

50 From the above description, it will be noted that the cock eyes upon the ends of the trace will be readily inserted between the fingers 4 and 5, the upturned portion 10 of the spring 9 readily admitting the said cock eyes, and the inclined under faces of the fingers 4 and 5 as well as the lip 7 prevents the accidental removal of the said 55 cock eyes.

Having thus fully described the said invention, what I claim is:—

A trace carrier comprising a skeleton 60 frame, having strap receiving openings, the said frame being formed with oppositely arranged upwardly inclined guards having 65 their inner edges rounded, the frame being further provided with arched fingers arranged centrally and transversely of the guards, one of said fingers being provided with a recess, the second finger being provided with a pocket, a flattened spring secured 70 within the pocket, said spring having its free end upturned and adapted to be received within the recess of the first named finger.

75 In testimony whereof I affix my signature in presence of two witnesses.

JACOB T. LUTZ.
